The Jonagold De Coster strain of Jonagold apple tree characterized particularly by the bright red color of its fruit, the high color percentage of its fruit, and by its freedom from virus infection.

4 Drawing Sheets**1**

This invention relates to a new and distinct variety of apple tree named Jonagold De Coster, sometimes denominated "Decosta".

The new apple variety was discovered in a cultivated orchard located in MOLENBEEK-WERSBEEK, Hageland, Belgium as a spontaneous whole tree mutation of Jonagold (Unpatented). Neither this tree nor its parent had been treated in any manner designed to induce sports.

The new apple tree cultivar was one of the block of apple trees propagated on M9 rootstock with Jonagold budwood. Its most unique characteristic is its desirable fruit color.

With respect to fruit color, Jonagold De Coster exhibits a higher degree of color development than standard Jonagold. Although as the percentage of red color on the fruit increases with the season, the shade of red color remains throughout the season the bright wine red color that standard Jonagold is known for. Its color characteristics may best be summarized in the following Table.

	Jonagold De Coster	Jonagored	Jonagold
Early color development of fruit	Similar to Standard Jonagold with some pink to red additional color visible from July through early September	Brownish brown-red color throughout the growing season, darkening and reddening in early September	Light green to dark green
Fruit finish color - shade	Very bright wine red tone similar to standard Jonagold with no brown tones. Finish tone is between 818 Jasper red and 818 Orient red, RHCC	Dark red to brown red; 821 Currant red to 822 Cardinal red, RHCC	Bright, wine red with white to yellow background
Fruit finish color - %	Many fruits with 85%-95% red color, some light stripes	Many fruits with 85-95% red color, some apples blush finish,	Many fruits with 20-30% red

RHCC — Royal Horticultural Colour Chart of London

With respect to virus, both the budwood and rootstock of the original mutation were controlled by the N.A.K.B. of Holland and labeled as virus free. The current scion wood in the U.S.A. also is virus free, as certified by the Washington State Department of Agriculture.

35 The new apple tree variety has been asexually propagated through three generations and its new characteristics shown to be stable and reproducible.

The three generations have been asexually propagated through T-budding and benchgrafting onto certified virus-free rootstocks. The trees of the first, second and third generation and 10,000 control trees in their second leaf in an orchard at Dronten, Holland have been controlled individually by the staff of the Belgian

National Research Station, the Dutch Fruit Advisory Team, and the staff of the Dutch Government Research Bureau.

More than 150,000 trees produced apples in 1991 in orchards planted in Belgium, The Netherlands, France, 5 and North, South and Eastern Germany. All the apples so produced were checked and found to be of uniform and stable color.

Also, the trees have been planted and observed in all of the research stations supervising apple variety trials 10 in Europe. These stations are located in Velm, Belgium; Wilhelminadorp, Zeewolde, Numansdorp, Horst, Geldermalsen, The Netherlands; York, Ahrweiler, and Bawendorf, Germany; Haidegg, Austria; Laimburg, Italy; Angers, Marsillarges, France, and elsewhere in 15 the world. In all of these stations Jonagold De Coster has been named among the best mutations of Jonagold.

IN THE DRAWINGS

FIG. 1 is a view of the Jonagold De Coster apple tree 20 variety of my discovery shown as it was discovered between a pair of standard Jonagold apple trees of the same stock, growing in the same block of trees.

FIG. 2 is an enlarged view of the new variety, illustrating the manner in which it was grown in Belgium, 25 slender spindle fashion, with wide branch angles.

FIG. 3 is an enlarged view illustrating the appearance and color of the mature fruits of the new apple tree variety.

FIG. 4 is a comparative display of the fruits of the 30 new apple variety in a mature state comparing them, with particular reference to color, with the standard Jonagold apple variety and the Jonagored apple variety in the same mature state.

FIGS. 5 and 6 are elevational and sectional views, 35 respectively of the new variety.

FIGS. 7, 8 and 9 are detailed views of the reference Jonagold strains, Jonagored, Rubinstar and Jonica.

FIGS. 10, 11 and 12 are comparative displays illustrating the appearance of the new apple variety in comparison with that of the reference Jonagold mutations 40 Jonagored, Rubinstar and Jonica.

In greater detail, the characteristics of the newly discovered Jonagold De Coster apple tree variety are as follows:

Tree: Upright, rather vigorous with wide spreading branches, medium in size, not as strong as Golden Delicious.

Bearing habit.—Medium size, regular annual 50 bearer, highly productive.

Trunk.—Thick, upright, smooth, gray color.

Branches.—Moderately thick, strong wide angles, very spreading, smooth gray bark.

Leaves.—Very large, medium to dark green with 55 green veins.

Spurs.—Strong, closely set.

Bark.—Gray, a somewhat lighter shade than standard Jonagold. This contrasts with the bark of the Jonagored variety which is a darker shade of 60 brown than that of standard Jonagold.

Lenticels.—Gray, obscure.

Disease status.—Virus free; susceptible to scab and mildew.

Vigor.—The same as standard virus-free Jonagold. 65

This compares with the vigor of Jonagored which is 15-30% less than standard due to the expression of apple rubbery wood virus.

Productivity.—Same as virus free Jonagold, but greater than Jonagored.

Pollination.—Bloom is mid-season. The variety is triploid with sterile pollen. Can be pollinated by: Alkmene, Benoni, Cox's Orange Pippin, Delcote, Discovery, Elan, Elise, Elstar, Fiesta, Gala, Gloster, James Grieve, Lombarts Calville, Melrose, Rafzubin, Vista Bella, Zoeta Oranje.

Fruit:

Shape.—Large fruit, high conical shape with the thickest point at half of the height, often leaning over going to the calyx end, very slightly ribbed.

Stem.—Long, 25 to 35 mm, thin.

Cavity.—Medium, obtuse, broad, shallow, light russet on some.

Calyx.—Large to medium large, closed, quite shallow.

Lobes.—Medium, broad, obtuse.

Basin.—Medium, wide obtuse, furrowed.

Skin.—Smooth, glossy, medium thickness and toughness.

Color.—Uniform bright wine red up into calyx and cavity, background color is yellow to light red, uniform pink-reddish nature begins in July covering a major portion of the fruit (80-95%) with finishing tone appearing in early September.

Lenticels.—Numerous, tan, obscure, almost invisible, very small points.

Calyx tube.—Long, narrow, funnel-shaped.

Stamen.—Median.

Core.—Small and round, closed.

Seeds.—Large, wide, tan to auburn.

Flesh.—White-yellow to yellow, firm, crisp, medium texture, juicy, sweet to aromatic-sour taste with outstanding flavor.

Quality.—Very good to excellent.

Storage.—Can be stored in regular cold storage until January and in ultra-low oxygen storage until July.

Further comparisons of the characteristics of my new apple variety Jonagold De Coster with standard Jonagold and the more significant Jonagold mutants, Jonagored, Rubinstar, Daliguy and Jonica (Schneica) are tabulated as follows:

TABLE I

Tree	Jonagold De Coster	Jonagored
growth	upright	vigorous
Bearing habit	rather vigorous	regular annual bearer
Trunk and branches	moderately thick	moderately thick
bark color	grey	dark brown
vigor	same as standard VF	Jonagored grows 5-10% more than standard VF
productivity	100%	90%
Tree	Standard VF Jonagold	Rubinstar
growth	upright	less upright
Bearing habit	less vigorous	much less vigorous
Trunk and branches	tendency to biannual	regular annual bearer
bark color	dark grey	very dark grey
vigor		virusinfected grows 10% less than Standard VF
productivity	100%	80%
Tree	Daliguy	Jonica

TABLE I-continued

growth	upright	less upright	
Bearing habit	less vigorous	much less vigorous	
Trunk and branches	tendency to biannual	regular annual bearer	
bark color	moderately thick	thin	
vigor	dark grey	grey	
	same as Standard VF	VF grows 10% less than Standard VF	
productivity	90%	80%	

TABLE II

	PICKING DATE	% FIRST PICK
Jonagold De Coster	9.19.1990	65.8
Jonagored	9.19.1990	61.8
Standard Jonagold	9.19.1990	20.0
Rubinstar	9.24.1990	86.5
Daliguy	9.19.1990	30.0
Jonica	9.26.1990	60.9

TABLE III

Fruit	Jonagold De Coster	Jonagored
Shape	not as large more uniform in size	very large not uniform size
Stem	globose conical	oblong conical
Calyx	long quite shallow	long shallow
Cavity	closed	some half-open
	broad	rather small
	medium deep	medium to little deep
Skin	smooth	smooth
Color	uniform wine-red	dark red to purple
	background green	little to no
	to yellow when ripe little	background
	striping	striping
Lenticels	numerous	numerous
Calyx tube	long narrow	long narrow
Core	small and round	small and round
Seeds	large wide	large wide
Flesh	white yellowish	yellowish
Fruit	Standard Jonagold	Rubinstar
Shape	large not uniform in size	smaller more uniform in size
	globose conical	flat globose
Stem	Long	medium long
Calyx	shallow	quite shallow
Cavity	some half-open	some half-open
	broad	broad
Skin	medium to deep	medium deep
Color	smooth	very smooth
	tomato red with a green to yellow background	uniform dark red with very little green
	little stripes	background
Lenticels	less	less
Calyx tube	not so long narrow	long narrow
Core	small and round	not small, and flat
Seeds	large wide	very small and very thin
Flesh	yellowish	yellowish
Fruit	Daliguy	Jonica
Shape	large not uniform in size	rather large not uniform in size

TABLE VIII

COMPARISON OF JONAGOLD MUTANTS		
(Selective sample of 5 apples)		
Appearance: * Color:		
Jonica:	uniform colored, dull brown red, the color changes gradually from green to red, the green side is green over the whole length.	
Jonagored:	dark red to purple, striped, almost no green color, change from green to red is very diffuse.	
Rubinstar:	uniform dark red, little green ground color, change from green to red is diffuse.	
DeCoster:	between bright and dark red, lightly striped, change from red to green is diffuse and not over the whole length.	
Lenticels:	DeCoster & Jonagored have many lenticels; Rubinstar and Jonica have a moderate number of lenticels.	
Shape:	Jonica and Rubinstar are rounded quadrangular; Jonagored: asymmetrical DeCoster: a little higher, a little sloping.	
Average number of pips:	Jonica: 3,0 Jonagored: 2,6 Rubinstar: 4,0 DeCoster: 2,6	
Diameter of core:	Jonica: 2,76 cm Jonagored: 2,88 cm Rubinstar: 3,18 cm DeCoster: 3,0 cm

(Source: Gegevens van de Nationale Proefuin voor Grootfruit, Sint-Truiden)

35 In summary, the unique characteristics of my newly discovered apple tree variety Jonagold De Coster are as follows:

The unique and striking color of the fruit, between dark and bright red.

40 Its original and continued virus free-status.

A high percentage of early first pick.

A vigorous and highly productive tree growth habit, creating a large tree volume with a very large potential fruit-bearing surface, which is well used.

45 Good fruit storage properties.

Superior fruit flavor.

I claim:

50 1. The new and distinct variety of apple tree as described and illustrated characterized particularly by the unique color of its fruit, by its unique virus free condition from inception, and characterized further by its high percentage of early first pick, a vigorous and highly productive tree growth habit, good fruit storage properties, and superior fruit flavor.
